UNITED STATES PATENT OFFICE

RAYMOND M. GRANDY, OF SUPERIOR, WISCONSIN

CAR REPLACER CLAMP

Application filed July 9, 1930. Serial No. 466,858.

This invention relates to new and useful improvements in car replacer clamps, and the principal object of the present invention is to provide an improved clamp for securing the replacer to the tracks, either for re-railing or de-railing purposes.

A further object of the invention is to provide a clamp of the above-mentioned character which is simple and durable in construction, consists of relatively few parts, reliable and efficient in operation, and otherwise well adapted for the purpose designed.

Other objects and advantages of the invention will become apparent during a study of the following description, taken in connection with the accompanying drawings wherein:

Figure 1 is a side elevational view of a clamping bar.

Fig. 2 is a top plan view thereof.

Fig. 3 is a front elevational view of a shoe which is adjustable on the clamping bar.

Fig. 4 is a side elevational view of the shoe.

Fig. 5 is a side elevational view of the clamping pin.

Fig. 6 is a side elevational view of the parts of the clamp in assembled relation when clamping the replacer in position for de-railing purposes.

Fig. 7 is a view similar to Fig. 6, showing the manner of using the clamp for re-railing purpose.

With reference more in detail to the drawings, it will be seen that my improved clamp comprises an elongated flat metal bar 5 adapted to extend under the rail R for supporting the rail on an intermediate portion of the bar, said bar 5 at one end, being provided with an upstanding flange or post 6.

As shown in Fig. 6, for re-railing purposes, a conventional type of car replacer is designated by the reference character P and the replacer is supported on the bar 5 between the railroad rail R and the flanged end of the bar 5, the flange 6 engaging the inner edge of the base of the replacer P, which is ordinarily provided with a flange as shown for forcing the lug L of the replacer against the web of the rail and hold the replacer in place relative to the rail as shown.

At its outer or free end, the bar 5 is pro-

vided with two longitudinal series of non-circular openings 7, 8, the non-circular openings 8 being arranged in staggered relation with respect to the non-circular openings 7. Adjustable on the bar 5 is a shoe designated 55 generally by the reference character 9 and embodying a sleeve portion 10 slidably receiving the bar 5, while at one end thereof, the shoe has projecting forwardly and upwardly from the upper edge of the sleeve 10 60 an arm 11 for overlapping engagement with the base flange of the rail R, with the forward edge of the arm 11 bearing against the web of the rail R.

To securely clamp the rail R against movement relative to the replacer P, and at the same time to retain the shoe 9 against movement relative to the rail, the shoe 9 is held at any point of adjustment through the medium of a retaining pin having an elongated 65 tapered shank at 12 to fit conformably within the non-circular opening of either series of openings 7, 8, the upper widest end of the shank merging into a lateral head 13, facilitating the insertion of the pin into one of the openings 7 or 8, and the removal of the pin from the openings in a manner apparent, and by suitable tools. In Fig. 7, I have shown my improved clamp used for re-railing purposes, and as is apparent, the function 70 and purpose of the several parts of the clamp are substantially identical with that as required for de-railing purposes, the only exception being that instead of the lug L of the replacer being clamped against one side 75 of the rail R there is inserted between the lug of the replacer P and the rail R, a suitable wooden block W, so that the wheels of the car will ride over the replacer P to slew over the block W and from the blocks to 80 the rail R.

It is thought that from the foregoing, taken in connection with the accompanying drawings, a clear understanding of the operation, construction, and utility and advantages of a replacer clamp of this character will be had by those skilled in the art without a more detailed description.

Even though I have herein shown and described the preferred embodiment of my in- 100

vention, it is understood that the same is susceptible to changes fully comprehended by the spirit of the invention herein described, and the scope of the appended claim.

- 5 Having thus described my invention what I claim as new is:—
- In a device of the character described, a replacer block provided with an integral lug adapted to engage one side of a rail web, the upper portion of the lug contacting the under face of the rail tread, and the lower portion of the lug contacting the base flange of the rail, a clamping plate having one end thereof adapted to support said replacer block, said clamping bar at said one end provided with a projection engaging the side of the replacer block remote from the rail, a sleeve member slidable on the clamping bar and having an integral forwardly and upwardly extending projection adapted to engage the opposite side of the rail web, said clamping bar provided with a series of staggered non-circular openings, and a retaining pin non-circular in cross section adapted to be disposed in a selected one of the openings for retaining said sleeve member at the desired adjustment on said bar.

In testimony whereof I affix my signature.

RAYMOND M. GRANDY.
